(57) **CLAIM**

We claim the ornamental design for a microwave oven, as shown and described.

DESCRIPTION

FIG. 1 is a front perspective view of a first embodiment of a microwave oven of the present invention;

FIG. 2 is a front view thereof;

FIG. 3 is a rear view thereof;

FIG. 4 is a first side view thereof;

FIG. 5 is a second side view thereof;

FIG. 6 is a top view thereof;

FIG. 7 is a bottom view thereof;

FIG. 8 is an enlarged front perspective view thereof;

FIG. 9 is a cross-section view taken along the line 9-9 of FIG. 4;

FIG. 10 is a front perspective view of a second embodiment of a microwave oven of the present invention;

FIG. 11 is a front view thereof;

FIG. 12 is a rear view thereof;

FIG. 13 is a first side view thereof;

FIG. 14 is a second side view thereof;

FIG. 15 is a top view thereof;

FIG. 16 is a bottom view thereof;

FIG. 17 is an enlarged front perspective view thereof; and,

FIG. 18 is a cross-section view taken along the line 18-18 of FIG. 13.

The broken lines represent unclaimed subject matter and form no part of the claimed design. Additionally, the dash-dot-dash lines around the control knob in FIGS. 1, 2, 8, 10, 11 and 17 define the limits of the claimed design.
